CLAIM

The ornamental design for a parking pay station video display cap, as shown and described.

DESCRIPTION

FIG. 1 is a top front perspective view of a parking pay station video display cap, showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a top front perspective view thereof, shown in a used condition mounted on a parking pay station shown in broken lines.

(Continued)

The broken lines shown in the drawings represent portions of the parking pay station that form no part of the claimed design.

1 Claim, 8 Drawing Sheets

It is certified that error appears in the above-identified patent and that said Letters Patent is hereby corrected as shown below:

On the Title Page

At page 2, Column 1, Lines 1-3, please delete "The broken lines shown in the drawings represent portions of the parking pay station that form no part of the claimed design." and replace with --The broken lines shown in FIG. 8 of the entire parking pay station form no part of the claimed design.--

Signed and Sealed this
Third Day of March, 2020

Andrei Iancu
Director of the United States Patent and Trademark Office
